METHOD OF MAKING NUTS AND THE LIKE

William L. Clouse, Tiffin, Ohio, assignor to The National Machinery Company, Tiffin, Ohio, a corporation of Ohio

Application April 6, 1933, Serial No. 664,749

28 Claims.

(Cl. 10—86)

This invention relates to the manufacture of nuts and the like by cold working. The present application is in part a continuation of my co-pending application Serial No. 656,126, filed February 10, 1933, and embodies certain features claimed therein.

The principal objects of the present invention are to produce finished polygonal nut blanks of substantially uniform size and volume by a series of cold working operations upon relatively inaccurate pieces of stock; to produce nut blanks having the corners chamfered on one surface and any desired finished configuration on the opposite surface from pieces of stock which may if wished have initially plain or unfinished faces, or which may have one face bevelled as shown in my said prior application; to eliminate the development of excessive pressures on the tools in all of the operations by performing each operation without completely confining at any time the metal of the blank so that the metal at all times may flow into one or more open spaces and thereby limit the maximum pressure that can be developed; and to simplify the operations and reduce the number of steps and die stages in the manufacture of nuts by cold working.

This invention consists in upsetting a blank into a polygonal die by partially piercing the blank so as to fill out one face to the desired configuration and allow the metal to flow freely toward the other face in such a manner as to produce a chamfer at the corners of such other face, and while held in a die exerting pressure against the faces of the blank to finish the faces and reduce the nut to the exact axial length desired, any excess volume of metal in the blank flowing into the pierced hole, and finally punching out an axial hole in the blank in alignment with the pierced hole and simultaneously punching out any excess metal that has flowed into the pierced hole. The invention also includes the novel upsetting step which may be used either in conjunction with the other steps of my process or in any other combination of steps and similarly the novel forming step for finishing the end faces which may likewise be used in any other desired combination of steps.

In the accompanying drawing which illustrates two embodiments of my invention:

50 Figure 1 is a view partly in section through a hexagonal die showing an illustrative form of tools for carrying out the first upsetting step;

Figure 2 is a similar view of tools which may be used for carrying out the second step;

Figure 3 is a similar view of a set of tools which

may be used alternatively to those shown in Figure 2 for carrying out the second step;

Figure 4 is a similar view of a set of tools which may be used for punching out the opening;

Figure 5 is a perspective view of a bar of stock 5 and a lozenger or rough blank sheared from the bar and from which a nut is to be formed.

Referring to the drawing, the first step is preferably carried out by confining a lozenger *a* in a hexagonal die *10* and acting on the opposite faces 10 of the lozenger by opposed tools *11* and *12*. The lozenger *a* may, if desired, be a rough substantially cylindrical piece sheared off from the end of a bar of stock and having substantially flat opposed faces *b* and *c*. Ordinarily, however, the 15 lozenger *a* is first subjected to a preliminary pressing operation as disclosed in my prior application to flatten the faces, remove any irregularities resulting from the shearing, and bevel the edge of one face to start the chamfer. 20

The tool *11* is arranged to move axially of the hexagonal opening in the die *10* and is formed at its end with a plunger *13* to enter and upset the metal of the lozenger *a*. The plunger portion *13* is connected to the body of the tool *11* 25 in any suitable way, preferably by a conical portion *14*. The tool *11* may be made substantially circular in cross section as illustrated in Figure 1 to enter between the opposite flat surfaces of the hexagonal die impression, or if desired may 30 be constructed hexagonal in section to closely fit the die.

The tool *12* as illustrated in Figure 1 may be formed with a hexagonal section to slidably fit in the die impression and is provided at its end 35 with a substantially flat face *15* having centrally disposed thereon a projection *16* united to the body of the tool *12* by a conical shoulder *17*.

In the first upsetting step the lozenger *a* is placed in the die *10* and is upset into the die impression by the tools *11* and *12* by moving the tool *11* to force the plunger *13* into the metal of the lozenger. The tool *12* may be moved or may simply be held in position to permit the metal to abut against the face *15* and the projection *16*. The action of the plunger *13* spreads the metal of the lozenger *a* radially into the die impression and throws the metal to cleanly and accurately fill out the corners adjacent the surface *15* of the tool *12*. During this action a 40 wave of metal *d* is thrown up around the plunger *13* from the upper face *b* of the lozenger. The metal of the blank is caused to flow bodily toward the tool *11*, increasing the axial length of the blank, and since the resistance to the metal 45

flow is greater around the periphery of the blank adjacent the walls of the die 10 than it is in the central portion of the blank or along the plunger 13, the metal spaced radially inward from the periphery of the blank flows axially to a greater extent than that adjacent the surfaces of the die 10, forming the upper face of the blank with a chamfer e.

The projection 16 on the tool 12 enters the metal of the lozenger and forms a recess f, of the same size and shape as the projection 16, in the lower face c of the blank. While the projection illustrated is shaped merely to form a counterbore for the hole, it will be understood that it may be of any desired shape. For example, this projection might be similar to, but smaller than, the plunger 13, as shown in my said prior application. During the upsetting operation the metal is free to flow axially toward the tool 11, since the upper face b of the lozenger is wholly unconfined radially outside of the plunger 13. The plunger 13 is pressed into the blank a predetermined distance, forming a pierced hole g separated from the recess f by a web of metal h. The thickness of this web of metal h remains substantially constant in each blank upset, although the volume of metal contained in the initial lozenger a may vary to a substantial extent. Any excess metal in the lozenger flows upwardly toward the tool 11 or increases the size of the wave d about the plunger 13 without being locked or confined so as to build up the pressures acting upon the tools.

At the completion of the upsetting operation as illustrated in Figure 1 the tools 11 and 12 are removed from the blank and the blank may be transferred to a die such as the die 18 illustrated in Figure 2. The die 18 is provided with a cavity 19 having a closed end 20. The closed end 20 of the die is formed substantially flat in the central portion and near its outer edges is formed with a chamfer 21 at the corners formed by the intersections of each two adjacent flat faces of the hexagon. A tool 22 having a substantially flat working face 23 formed with a central projection 24 is arranged to slidably fit in the die cavity 19. Preferably the face 23 and the projection 24 are the same in configuration as the face 15 and projection 16 of the tool 12. The closed end 20 of the die 18 is formed with the configuration which it is desired to impart to the upper or chamfered face of the finished nut and likewise the face 23 of the tool 22 preferably conforms to the desired finished bottom face of the nut. The die cavity 19 may simply be formed in a solid block or the die may be assembled from any suitably shaped pieces leaving the cavity 19. The closed end 20 of the die may simply be the forward face of a knockout pin 60 which is held stationary during the pressure operation. A knockout pin may, of course, also be of a smaller diameter to slide through the end 20.

The total 22 is pressed into the die cavity 19 against the blank until the axial height of the blank is reduced to the desired size and the upper face is pressed into the desired finished form against the closed end 20 of the die. During this operation the wave d formed on the upper face b of the lozenger in the initial operation is pressed back into the blank, any excess metal flowing into the pierced hole g. The chamfer e formed by the drag of the metal of the blank in the die 10 during the first upsetting step is shaped to the desired finished form by the chamfer 21 in the die 18. Any excess volume of metal initially present in the lozenger a is likewise pressed into the pierced hole g and by reason of the freedom of the metal to flow into this hole the pressures developed by moving the tool 22 through the predetermined distance are limited to the pressure required to make the metal flow and cannot build up to a point which would injure the tools.

At the completion of this operation an axial hole is punched completely through the blank in alignment with the recess f formed in the bottom face of the blank and the pierced hole g formed in the top face. Preferably the hole is punched to the same size as the flat end of the recess f, leaving the conical portion of the recess as a counterbore for the lower end of the hole. This punching operation may be performed in the usual manner by merely placing the blank over an apertured plate and bringing the punching tool down through the blank, preferably first entering the recess f in order to avoid distorting the counterbore, or the punching may be carried out with the metal of the blank confined in the same or another die such as illustrated in Figure 4, as will be explained more in detail hereinafter.

It will be understood, of course, that in connection with the tools shown in Figures 1 and 2 the projections 16 and 24 may be omitted, if it is desired to omit the counterbore or to form it in some other way, and if the partial piercing provided by these projections is unnecessary. Likewise the tools 12 and 22 may be given any other contour to form the bottom face of the completed nut as desired.

An alternative form of tools for carrying out the second step is illustrated in Figure 3, and this figure also illustrates an arrangement to form a washer face on the bottom face of the nut which, of course, may also be utilized in the embodiment first described. In the embodiment shown in Figure 3 the blank at the completion of the first upsetting step is placed in a confining die 25 and is acted upon by opposed tools 26 and 27. The tool 26 is formed with a flat face 28 and a projection 29 to conform to the desired finished bottom face of the nut and as illustrated is formed with a circular section and is arranged to slide through a ring 30 retained in the die 25 to form a washer face or recess j on the nut. The tool 26 is preferably brought up to a position to support the nut blank with its chamfered upper end projecting above the flat upper face 31 of the die 25. The tool 27 is formed with a recess 32 preferably flat in its central portion and provided with a hexagonal chamfer 33 to shape and finish the upper end of the blank to the desired contour. The tool 27 is brought down against the projecting upper face of the blank through a predetermined distance so that the blank is reduced to the desired axial height and is shaped to the desired finished form by the recess 32. During this operation the wave of metal d thrown up on the upper face of the blank is pressed into the pierced hole g and likewise a portion of any excess volume of metal contained in the blank is caused to flow into the pierced hole g as in the operation illustrated in Figure 2. The tool 27, however, is not formed to enter the die 25, but is formed with a flat surface 34 radially outward of the recess 32 which approaches the end surface 31 of the die 25 causing a flash of metal k to be thrown out between these surfaces 31 and 34. The metal of the lower face of the blank is pressed down against

the ring 30, forming the recess *j*, and completing the filling out of the corners at the lower face immediately above the recess. The remainder of any excess volume of metal contained in the blank 5 is thrown out into the flash *k* so that the blank is reduced to the desired axial height while being confined externally by the die 25 and the excess metal flows either into the pierced hole *g* or outwardly into the flash *k*. As in the preceding 10 operations the pressures developed within the blank are limited by the fact that the pierced hole *g* is unconfined and the metal can freely flow into this hole.

In Figure 4 I have shown an arrangement of 15 tools which may be employed as another alternative for pressing the blank to the desired axial height and for punching out the axial opening in the blank. The blank is placed within a confining die 35 and is engaged on its opposite end 20 faces by hollow tools 36 and 37 which press to size and firmly hold the blank against distortion. A punch 38 is slidably arranged within the hollow tool 37 and after the blank has been pressed to the desired axial height, the punch is forced completely through the same, entering preferably the 25 recess *j* and then shearing out the web *h* and shaving away the metal which has been pressed into the pierced hole *g* by the finishing operations for the end faces. If the blank is formed 30 with a washer face the die 35 may be provided with a ring 39 within which the tool 37 slides. This ring 39 is forced into the metal to form the recess *j* and complete the filling out of the lower corners in the same way as the ring 30 previously 35 described. Being held in the confines of the die during the finishing operation for the end faces, and then for the punching operation, the blank is punched with an axial hole that is accurately concentric and aligned with the periphery of the 40 blank and likewise accurately perpendicular to the end faces, since the punching operation is carried out while the blank is firmly held against distortion.

Where the end faces of the blank are finished 45 by the type of apparatus illustrated in Figure 3 the flash *k* may be sheared off either in a separate operation or when the blank is inserted into the die 35 or in any other convenient way.

It will also be evident that if desired the punching 50 operation may be carried out in conjunction with the end face finishing operation as illustrated in Figure 3. This may be done by constructing the tool 27 hollow in the manner of the tool 36, and likewise constructing the tool 26 hollow and slidably mounting therein a punch corresponding to the punch 38. After the tool 27 55 is brought down through the desired distance and the end face of the blank finished to the desired contour the punch may then be pressed into and through the blank without relieving the pressure 60 on the side or end faces exerted by the tools. The flash *k* may then be sheared off in any suitable way and the blank is completed.

Similarly the punching operation may be combined with the operation of the tools illustrated in 65 Figure 2 by simply providing an opening through the closed end 20 of the die 18 and slidably mounting the punch within the tool 22. Furthermore, the punching operation can be performed 70 from the top face of the nut, if wished, by arranging the punch in the tools 17, 21 or 36.

Although I have described my invention with 75 reference to particular embodiments and tools, it will be understood that the invention is not limited to any particular type or form of apparatus and

that many changes, modifications and rearrangements of steps and details may be resorted to without departing from the scope of the invention as defined in the following claims.

I claim:

1. The process of making nuts by cold working comprising shearing off a length of stock from a bar, upsetting and spreading the metal into a polygonal form by partially piercing the length of stock, retracting the piercing tool from the 10 stock, finishing the end faces of the length of stock and reducing the stock to the desired axial length, and maintaining at least one surface of the metal unconfined during each operation to permit a free flow of the metal at such surface 15 to limit the pressures developed in the operations and to dispose of any excess volume of metal.

2. The process of making nuts by cold working comprising shearing off a length of stock from a bar, upsetting and spreading the metal into a 20 polygonal form by partially piercing the length of stock, retracting the piercing tool from the stock, finishing the end faces of the length of stock and reducing the stock to the desired axial length, and maintaining at least one surface of 25 the metal unconfined during each operation to permit a free flow of the metal at such surface to limit the pressures developed in the operations and to dispose of any excess volume of metal, and then punching out an axial opening in the 30 blank.

3. The process of making nuts by cold working comprising confining a blank in a polygonal die, upsetting the blank into the die by partially piercing the same from at least one end surface, 35 carrying out the piercing operation to flow the metal of the blank axially toward the piercing tool to elongate the blank and to a greater extent adjacent the piercing tool than adjacent the walls of the die, exerting pressure on the opposite 40 end faces of the blank, while the same is confined externally, to finish the end faces and reduce the blank to the desired axial length, and punching out an axial opening in the blank.

4. The process of making nuts by cold working 45 comprising confining a blank in a polygonal die, upsetting the blank into the die by partially piercing the same from at least one end surface, carrying out the piercing operation to flow the metal of the blank axially toward the piercing 50 tool to elongate the blank and to a greater extent adjacent the piercing tool than adjacent the walls of the die, exerting pressure on the opposite end faces of the blank, while the same is confined externally, to finish the end faces and 55 reduce the blank to the desired axial length, and without removing the pressure on the end faces or removing the blank from the confining die, punching the blank axially to form a hole there-through and shear out any excess metal.

5. The process of making nuts by cold working comprising confining a blank in a polygonal die, upsetting the blank into the die by partially 65 piercing the same simultaneously from the opposite ends, and carrying out the piercing from one end through a greater depth than from the other to cause the metal of the blank to flow axially toward said one end to elongate the blank and through a greater extent adjacent the piercing tool than adjacent the walls of the die, exerting 70 pressure on the opposite end faces of the blank, while the same is confined externally, to finish the end faces and reduce the blank to the desired axial length, and punching out an axial opening in the blank.

5

75

6. The process of making nuts by cold working comprising confining a blank in a polygonal die, upsetting the blank into the die by partially piercing the same from the opposite ends, and carrying out the piercing from one end through a greater depth than from the other to cause the metal of the blank to flow axially toward said one end to elongate the blank and through a greater extent adjacent the piercing tool than adjacent the walls of the die, exerting pressure on the opposite end faces of the blank, while the same is confined externally, to finish the end faces and reduce the blank to the desired axial length, and without removing the pressure on the end faces or removing the blank from the confining die, punching the blank axially to form a hole therethrough and shear out any excess metal.
7. The process of making nuts by cold working comprising upsetting a blank into a polygonal shape by partially piercing the same, forming a chamfer on at least one end face of the blank and during each operation maintaining at least one surface of the blank unconfined so as to permit a free flowing of the metal at such surface, reducing the pierced blank to the desired finished axial length, allowing any excess metal to flow into the pierced hole and punching out an axial opening in the blank in alignment with the pierced hole and at the same time punching out any excess metal.
8. The process of making nuts by cold working comprising upsetting a blank into the confines of a polygonal die by partially piercing the same, retracting the piercing tool to free the surface of the pierced hole, exerting pressure on the opposite ends of the blank to reduce the blank to a desired axial length and simultaneously press a peripheral chamfer upon one end face of the blank, and punching out an axial opening in the blank.
9. The process of making nuts by cold working comprising upsetting a blank into the confines of a polygonal die by partially piercing the same, retracting the piercing tool from the blank, exerting pressure on one end face of the blank by a concave tool surface to form a chamfer on that end face, and punching out an axial opening in the blank.
10. The process of making nuts by cold working comprising upsetting a blank into the confines of a polygonal die by partially piercing the same, retracting the piercing tool from the blank, pressing the blank axially into a die having a closed chamfered end to form a chamfer on one end face of the blank, and punching out an axial opening in the blank.
11. The process of making nuts by cold working comprising upsetting a blank into polygonal form by partially piercing the same from one end surface to flow the metal of the blank toward the piercing tool, leaving such end surface unconfined in an axial direction over an area radially outward of the piercing tool and with the other end face restricted, pressing the pierced blank on said one end face by a concave tool surface to form a chamfer on the blank, and punching out an axial opening in the blank.
12. The process of making nuts by cold working comprising upsetting and chamfering a blank by confining the same in a polygonal die partially piercing the same from one end surface, leaving said end surface wholly unconfined in an axial direction radially outward of the piercing tool, pressing the blank axially into a die having a closed end to shape said one end surface against

the closed end of the die and punching out an axial opening in the blank.

13. The process of making nuts by cold working comprising upsetting and chamfering a blank into polygonal form by partially piercing the same axially from one end surface, leaving said one end surface unconfined in an axial direction over an area radially outward of the piercing tool, pressing the blank axially into a die having a closed chamfered end to further shape on said one end surface and punching out an axial opening in the blank.

14. The process of making nuts by cold working comprising upsetting a blank into polygonal form by partially piercing the same through more than half of the axial length of the blank, supporting the blank in a die with one end surface projecting therefrom, pressing said one end surface to form a chamfer thereon and punching out an axial opening in the blank.

15. The process of making nuts by cold working comprising upsetting a blank into polygonal form by partially piercing the same, supporting the blank in a polygonal confining die with one end thereof projecting from the die and exerting a pressure against said projecting end to form a chamfer thereon and throw out a flash at the intersection of the chamfer and the polygonal sides of the blank and punching out an axial opening in the blank.

16. The process of making nuts by cold working comprising confining a blank in a polygonal die, upsetting the blank into the die by partially piercing the same from at least one end surface, and carrying out the piercing operation to flow the metal of the blank axially toward the piercing tool to elongate the blank and to a greater extent adjacent the piercing tool than adjacent the walls of the die.

17. The process of making nuts by cold working comprising confining a blank in a polygonal die, upsetting the blank into the die by partially piercing the same simultaneously from the opposite ends, and carrying out the piercing from one end through a greater depth than from the other to cause the metal of the blank to flow axially toward said one end to elongate the blank and through a greater extent adjacent the piercing tool than adjacent the walls of the die.

18. The process of making nuts by cold working comprising confining a blank in a polygonal die, upsetting the blank into the die by partially piercing the same from at least one end surface leaving the blank throughout the piercing operation and until the retracting of the piercing tool unconfined on that end surface in an axial direction radially outward of the piercing tool, and carrying out the piercing operation to flow the metal toward the unconfined end surface to elongate the blank and through a greater extent adjacent the piercing tool than adjacent the walls of the die.

19. The process of making nuts by cold working comprising confining a blank in a polygonal die, upsetting the blank into the die by partially piercing the same from the opposite ends, leaving the metal of one end surface unconfined in an axial direction over an area radially outward of the piercing tool, and carrying out the piercing from the unconfined end through a greater depth than from the other end to cause the metal of the blank to flow axially toward said unconfined end to elongate the blank and through a greater extent adjacent the piercing tool than adjacent the walls of the die.

20. The process of making nuts by cold working comprising supporting a blank in a polygonal confining die and partially piercing the blank from at least one end surface in such a manner 5 as to cause the metal to flow along the piercing tool in the opposite direction to the movement of the tool, and to flow in the same direction along the walls of the confining die.

21. The process of making nuts by cold working 10 comprising confining a blank in a polygonal die, upsetting the blank into the die by partially piercing the same from at least one end surface, leaving the blank throughout the piercing operation and until the retracting of the piercing tool un- 15 confined on that end surface in an axial direction radially outward of the piercing tool, and restricted on the opposite end surface and carrying out the piercing operation to flow the metal toward the unconfined end surface to elongate 20 the blank.

22. The process of making nuts by cold working comprising confining a blank in a polygonal die, upsetting the blank into the die by partially piercing the same simultaneously from the opposite 25 ends, leaving the metal of one end surface un- confined in an axial direction throughout said piercing operation over an area radially outward of the piercing tool, and carrying out the piercing from the unconfined end through a greater depth 30 than from the other end to cause the metal of the blank to flow axially toward said unconfined end to increase the axial length of the blank to substantially the desired height of the finished nut.

35 23. A process of making nuts by cold working comprising upsetting a blank into a polygonal die by partially piercing the same, retracting the piercing tool to free the surface of the pierced hole, and pressing one face of the blank to form 40 an axial projection thereon and to flow the metal to completely fill out the corners of the blank adjacent said one face.

24. A process of making nuts by cold working 45 comprising upsetting a blank into a polygonal die by partially piercing the same, retracting the piercing tool to free the surface of the pierced hole, exerting pressure on the opposite end faces of the blank to reduce the blank to the desired axial length, and pressing the metal on one end

face adjacent the corners of the blank to completely fill out the corners in a plane spaced slightly from the plane of said one end face.

25. A process of making nuts by cold working 5 comprising upsetting a blank into a polygonal die by at least partially piercing the same, retracting the piercing tool to free the surface of the pierced hole and exerting pressure against one end face of the blank to form a washer face thereon by axially flowing the metal adjacent the corners of 10 the blank spaced radially from the pierced hole.

26. The process of making nuts by cold working comprising upsetting a blank into a polygonal die by at least partially piercing the same, exerting pressure on the opposite end faces of the blank 15 to reduce the same to the desired axial length, allowing any excess metal to flow into the pierced hole, pressing one end face of the blank to axially flow the metal adjacent the corners of the blank radially spaced from the pierced hole to completely fill out the corners of the blank adjacent 20 said one end face and form a washer face thereon, and punching out an axial opening in the blank.

27. That method of making a nut by cold working 25 which comprises shearing off a length of wire or rod stock to provide a cylindrical blank, shaping said cut off blank, confining said blank in a polygonal die, piercing to upset the same into the corners of the die and flow the metal of the blank axially to increase the height of the blank, finishing 30 the upper and lower faces of the pierced blank by pressure thereon with the pierced hole unconfined to permit excess metal to flow into the pierced hole and punching out the pierced hole. 35

28. That method of making a nut by cold working 40 which comprises shearing off a length of wire or rod stock to provide a cylindrical blank, shaping said cut off blank by axial pressure on the blank, confining said shaped blank in a polygonal die, piercing the blank from one end surface through more than half the axial length of the pierced blank to upset the same into the corners of the die and flow the metal of the blank axially to increase the height of same, finishing the upper and lower faces of the pierced blank by pressure 45 thereon with the pierced hole unconfined to permit excess metal to flow into the pierced hole and punching out the pierced hole.

WILLIAM L. CLOUSE.
